CLAIM

The ornamental design for a rotating modular album holder and supporting base therefor, as shown and described.

DESCRIPTION

FIG. 1 is a top plan view of a rotating modular album holder and support base therefor showing my new design;

FIG. 2 is a side elevational view thereof;

FIG. 3 is a bottom plan view thereof; and

FIG. 4 is an enlarged scale isometric view of one module of the rotating modular album holder portion of the rotating modular album holder and supporting base therefor of FIG. 1.

FIG. 1

FIG. 2

H-10 - 3
